UNITED STATES PATENT OFFICE.

FRED C. SCHOENTHAL, OF BUFFALO, NEW YORK, ASSIGNOR, BY MESNE ASSIGNMENTS, TO STEEL WHEEL CORPORATION, OF LANSING, MICHIGAN, A CORPORATION OF MICHIGAN.

WHEEL.

Application filed June 29, 1922. Serial No. 571,811.

This invention relates to an improvement in wheels and particularly to an improvement in wheels of the disk type.

One object of this invention is to provide 5 a disk wheel having a single convex concave tapered disk.

Another object is to provide clutch acting driving means which also support the disk at the hub and relieve the assembling pins 10 from all driving strain.

A further object of the invention is to provide in a disk wheel a rim of varying thickness, the flange portions being the thickest and the base the thinnest.

15 Another object of the invention is to provide a disk wheel with a rim having an annular groove against which a portion of the wheel disk is positioned.

Other objects will appear from a consideration 20 of the specification and of the drawings which form a part thereof and in which

Figure 1 is a section taken on the line 1—1 of Fig. 2 disclosing one embodiment 25 of this invention;

Fig. 2 is a fragmentary front elevation on a smaller scale of the embodiment shown in Fig. 1;

Fig. 3 is a section taken on the line 3—3 30 of Fig. 4 showing another embodiment of this invention;

Fig. 4 is a fragmentary front elevation on a smaller scale of the embodiment shown in Fig. 3;

35 Fig. 5 is a cross section of a third embodiment of this invention taken on the line 5—5 of Fig. 6;

Fig. 6 is a fragmentary front elevation on a smaller scale of the embodiment shown 40 in Fig. 5;

Fig. 7 is a detailed view of one of the lock washers employed in this invention and

Fig. 8 is a cross section on a larger scale 45 of the rim of the embodiment shown in Fig. 3.

Referring to the drawings and particularly to the embodiment shown in Figs. 1 and 2, the reference numeral 10 designates the hub member which is mounted on an axle 50 11. On the hub member is provided an annular flange 12 having an annular shoulder 13 and a conical face 14. The flange 12 also has a series of pockets 15 thru the bottom of which are provided openings 16. In 55 each of the openings 16 is mounted a bolt

17 having a shoulder 18 intermediate its length. The bolt is held in place on the flange by a nut 19 which firmly clamps the flange against the shoulder.

The wheel disk 20 has a central opening 21 of a diameter greater than that of the annular shoulder 13. Around the opening 21 are provided apertures 22 thru which the bolts 17 extend when the disk and hub are assembled. The apertures 22 at the face of the disks are recessed as at 23 for a purpose to be described below.

Rigidly secured to the back of the disk 20 is a ring 24, the inner face 25 of which is conical so that when the disk and hub are assembled the face 25 will bear against the face 14 of the flange. It will thus be noted that the full weight of the wheel is carried thru these cooperating faces which form clutch surfaces locking the disk in place on the hub and in addition to carrying the weight act to transmit the power between the disk and the hub. At the same time all driving and shearing strain on the bolts 17 is eliminated together with the vertical 80 and side stresses.

The hub portion of the disk lies in a plane 26 in front of and parallel to the center longitudinal plane 27 of the wheel. At an equal distance behind the plane 27 is a plane 28 which is parallel to the plane 26. These two planes 26 and 28, between which the disk is located, thus limit its contour. The portion 29 of the disk which bears against the flange 12 is thickest and, as pointed out above, lies in the plane 26. The disk is curved convexly from the plane 26 to the center plane 27, and then concavely touching the plane 28 at its deepest point 30 and returning to the center plane 27 again. The disk is now curved convexly touching the plane 26 at 31 and finally terminates in a U formed by a peripheral flange 32 concentric with the axis of the wheel and extending to the plane 28. That portion of the disk which acts as a felly and to which the rim is secured provides an annular pocket 33 at the back of the disk.

It will be noted that the disk crosses the center plane 27 of the wheel three times, i. e., at 34, 35 and 36, thus giving resiliency and strength to the light disk. By reason of this construction the disk acts to absorb wheel shocks and crystallization of the metal is prevented. Also as shown particularly in

Fig. 1 the disk tapers from the hub portion 29 to the peripheral flange 32 where it engages the rim. The rim 37, as shown in Fig. 1, has an annular groove 38 against which the juncture of the disk and flange bears in order to properly position the disk with relation to the rim. This rim is preferably arc-welded to the flange but any suitable fastening means may be employed.

10 Seated in the groove 38 is the rim ring 39.

The disk 20 is clamped onto the flange 12 and the shoulders 18 by caps 40 threaded onto the bolts 17. The inner ends of these caps bear against the recess 23 around the apertures and not against the face of the disk. Hence when the cap is tightened there is no danger of cracking the enamel on the face of the disk. Fastened inside the cap 40 by a rivet 41 or suitable means, is a lock washer 42. As shown in Fig. 7 this washer is slotted to provide spring tongues 43 which are normally bent out of the plane of the washer, so that when the cap is tightened these tongues will bear against the end of the bolt 17 and prevent loosening of the cap.

The embodiment shown in Fig. 3 and Fig. 4 discloses a wheel similar in many respects to the embodiment shown in Figs. 1 and 2 and in so far as it is similar the same reference characters have been used. Instead, however, of a hub which has an integral flange this embodiment discloses the use of an ordinary wood wheel hub provided with an adapter by which the disk 20 is carried. The adapter 50 is slipped over the wood wheel hub 51, an opening 52 being provided, and is secured to the rear flange 53 of the hub 51 by bolts 54. In order to make this adapter as light as possible it will be noted that the metal is cut away to provide an annular recess 55 and integral annular flanges 56 which bear against the flange 53. The heads of the bolts 54 rest in pockets 57 provided in the face of the adapter. A shoulder 58 above the opening 52 positions the disk 20 functioning in the same manner as the shoulder 13 in Fig. 1. At the outer edge of the adapter is provided a conical seat 59 which is engaged by the ring 24 of the disk to support the disk out of contact with the shoulder 58 and transmit the driving forces.

The rim 60 is tapered transversely, the flanges 61 being thicker than the base 62. By reducing the thickness of the base the weight of the rim is cut down and inasmuch as the flange 32 of the disk is firmly secured to that portion of the rim the strength of the wheel is not sacrificed by reducing the thickness of the base 62. In the rim 60 is provided an annular groove 63 against which the point of juncture of the disk and the flange bears.

65 Rigidly fastened in the rim and passing

thru suitable openings in the flange 32 and the face of the disk is a tube 64 in which the valve stem is inserted. The tire may thus be inflated or deflated from the front without demounting the wheel and without the use of air valve covers in the disk. This same construction is provided in the embodiment shown in Figs. 1 and 2 but the view there given does not bring out so clearly the relation of the tube to the disk. It will be noted, however, that the tube 64 is shown in Fig. 2 protruding thru the disk.

In place of the six bolts 17 used in the first embodiment as indicated on Fig. 2 only three bolts 17 are used, as shown by the caps 40 on Fig. 4, the bolts 17 alternating with the bolts 54 by which the adapter is secured to the hub.

The embodiment shown in Figs. 5 and 6 differs from that shown in Fig. 1 only in the shape of the disk. In place of the disk 20 having a rounded convex concave contour is substituted a disk 70 which projects at the hub portion beyond the line 26 and extends in a straight line from the hub portion 71 to the plane 28. The disk then follows the plane 28 to the point 72 where it returns to the plane 26 at 73 along a line 74 which is at right angles to the line 75 designating the direction of the disc from the hub portion 71 to the plane 28. The disk now follows the plane 26 to the rim 37 where a flange 76 is provided to which the rim 37 is rigidly secured.

While certain embodiments of this invention have been shown and described, applicant is not to be limited thereby since it is obvious that others may be made without departing from the spirit and scope of the invention as set forth in the following claims.

Having thus set forth my invention that which I claim as new and for which I desire to obtain the protection of Letters Patent in the United States is the following:

1. In a disk wheel, a hub having an annular radial flange, said flange having a conical surface, a disk having a central opening through which the hub projects, a ring rigidly secured to said disk, surrounding the opening therein, and having its inner face conical.

2. In a disk wheel, a wheel disk ring rigidly secured to the back of the disk between the hub and the rim portions and having its inner face conical and a hub having a flange with a conical face which said ring engages when the disk is assembled on the hub.

3. In a disk wheel, a hub member having an annular flange with a conical face, a disk member having a central opening through which the hub member projects when the wheel is assembled, a ring rigidly secured to one face of said disk, surrounding said opening and having an inner coni-

cal face adapted to seat on the conical face of said flange when the wheel is assembled and means removably holding said members in assembled position.

5 4. In a disk wheel, a hub member having an annular flange provided with an annular shoulder on one side and a conical face, a disk member having a central opening of a diameter greater than that of the annular shoulder, a ring rigidly secured to said disk surrounding said opening and having a conical inner face which rests on the conical face of said flange and bolts carried by said flange by which said members are removably held in assembled position.

10 5. In a disk wheel, a hub member having an annular flange provided with an annular shoulder on one side and a conical face, a disk member having a central opening of a diameter greater than that of the annular shoulder, a ring rigidly secured to said disk surrounding said opening, and having a conical inner face which rests on the conical face of said flange, a series of apertures in said disk member, a series of bolts carried by said flange adapted when said members are assembled to project through said apertures and caps removably holding said disk member in position.

15 6. In a disk wheel, a hub member having an annular flange provided with an annular shoulder on one side and a conical face, a disk member having a central opening of a diameter greater than that of the annular shoulders, a ring rigidly secured to said disk surrounding said opening and having a conical inner face which rests on the conical face of said flange, a series of apertures in said disk member, a series of bolts carried by said flange adapted when said members are assembled to project through said apertures, caps removably holding said disk member in position and lock washers holding said caps in place.

7. In a disk wheel, a hub, an adapter carried by and rigidly secured to said hub, said adapter having an annular shoulder and a conical face, a disk having a central opening of a diameter larger than that of the shoulder and a ring on said disk having a conical inner face engaging the face of said adapter when the wheel is assembled.

8. In a disk wheel, a hub, an adapter carried by and rigidly secured to said hub, said adapter having an annular shoulder and a conical face, a disk having a central opening of a diameter larger than that of the shoulder, a ring on said disk having a conical inner face, engaging the face of said adapter when the wheel is assembled, and means for securing said adapter to said hub and said disk to said adapter.

9. In a disk wheel, a hub, an adapter carried by and rigidly secured to said hub, said adapter having an annular shoulder and a conical face, a disk having a central opening of a diameter larger than that of the shoulder, a ring on said disk having a conical inner face engaging the face of said adapter when the wheel is assembled, means for securing said adapter to said hub, and means independent of said adapter securing means for securing said disk to said adapter.

10. In a disk wheel, a hub, an adapter carried by and rigidly secured to said hub, said adapter having an annular shoulder and a conical face, a disk having a central opening of a diameter larger than that of the shoulder, a ring on said disk having a conical inner face engaging the face of said adapter when the wheel is assembled, means for securing said adapter to said hub, and means independent of said adapter securing means for removably securing said disk to said adapter.

In testimony whereof, I affix my signature.

FRED C. SCHOENTHAL.
